UNITED STATES PATENT OFFICE.

JOHN WILLIAM EARLE AND ALFRED BOURNE, OF BIRMINGHAM, ENGLAND; SAID
BOURNE ASSIGNEE TO SAID EARLE.

APPARATUS FOR MAKING METAL-CASED TUBES.

946,022.

Specification of Letters Patent. Patented Jan. 11, 1910.

Application filed June 19, 1909. Serial No. 503,090.

To all whom it may concern:

Be it known that we, JOHN WILLIAM EARLE and ALFRED BOURNE, subjects of Great Britain, residing at Birmingham, England, have invented new and useful Improvements in Apparatus for Making Metal-Cased Tubes, of which the following is a specification.

This invention has for its object the expeditious production at small cost of metal cased tubes of the type in which a locking strip is inserted between the case and the inner tube for securing together the edges of the case.

The invention relates to the features of construction and combination and arrangement of parts hereinafter set forth and particularly described in the claims.

Referring to the three accompanying sheets of explanatory drawings;—Figures 1, 2 and 3 are respectively side elevation, plan and sectional side elevation of tools or dies adapted in accordance with this invention for producing tubes of the type aforesaid. In Figs. 1 and 2 the case, locking strip, and inner tube are also shown in position, but in Fig. 3 the case and locking strip are omitted for clearness. Fig. 4 is a side elevation and Fig. 5 a plan of the guide piece for guiding the locking strip into position; Figs. 6 and 7 are elevations taken at opposite ends of the guide piece while Fig. 8 is a cross section on A A Fig. 4. Figs. 9 to 14 illustrate the shapes of successive portions of the dies at the lines B to G (Fig. 1) and the corresponding shapes of the tube portions passing therethrough. Figs. 4 to 14 are drawn to a larger scale than Figs. 1 to 3.

The same reference letters in the different views indicate the same parts.

In carrying the invention into effect as illustrated the bending and drawing of the case strip *a* on to the ordinary inner tube *b* is effected by a die which for convenience is made in sections united or secured in the necessary alinement by screws, a holder, or any other suitable means.

The front section *c* of the die is provided with a U-shaped channel which is bell mouthed at its outer end and tapered in the direction of its length. Such section is covered by a plate *d* having grooves *e* with central ridge *o* formed on its underside for guiding the edges of the case strip and gradually drawing them together. The

cover plate *d* does not cover the whole of the section *c* but leaves a portion at its rear edge exposed as shown in Figs. 1 to 3. The shape of the front end of the die aperture in the section *c* at the position corresponding to line B. B. (Fig. 1) is shown at Fig. 9 while the shape at or near the rear of that section (line C. C. Fig. 1) is shown at Fig. 10.

The middle section *f* of the die contains a tapered aperture the configuration of which changes from an oval form as shown at Fig. 1 (line D. D. Fig. 1) at one end to the approximately circular form shown at Fig. 12 (line E. E. Fig. 1) at the other end. Along the upper side of such aperture a central ridge *g* is provided for the purpose herein-after described. The rear section *h* of the die comprises an aperture which passes from the shape shown at Fig. 13 (line F. F. Fig. 1) at its front end to the exactly circular form shown at Fig. 14 (line G. G. Fig. 1) at its rear end, the latter corresponding to the dimensions of the finished tube. Each section is bell mouthed at the entrance to its aperture to avoid a sharp ridge between the sections.

In conjunction with the front and middle portions *c* and *f* of the die there is arranged a loose guide piece *i*. At one extremity of such piece is formed an upwardly projecting shoulder *j* adapted to enter a slot *k* in the plate *d* aforesaid, for preventing the piece from being drawn forward with the tube. The portion of the guide piece which enters the die is tapered in the direction of its length and is formed with a slot *l* at its forward extremity to pass along each side of the ridge *g* above referred to in the middle section of the die. On its upper side the guide piece is made convex to correspond with the shape of the die aperture in which it lies, while at its underside it is made concave to correspond with the circumference of the inner tube *b*. Along the underside a slot *m* is also formed to receive the locking strip *n* of the tube.

Prior to forming a tube, the front end of the inner tube *b* is inserted through the die together with a portion of the case strip *a* and the locking strip *n* which is preferably shaped previously to a channel section. In some cases the locking strip may be shaped by the guide piece *i*. The said guide piece is also placed in position. On drawing the

inner tube, case and locking strip through the die, the sides of the case strip *a* are gradually closed over on to the inner tube. The edges are also turned inward by the action 5 of the ridge *g* in the central section of the die and caused to enter the locking strip which is guided into position by the slot *m* in the underside of the guide piece *i*. Subsequently the edges of the two strips are 10 closed tightly together, and the case further closed on to the inner tube. By the action of the last section of the die, the tube is completed. The successive stages in the formation of the complete tube are clearly shown 15 by the sectional views at the right hand sides of the views showing the dies in Figs. 9 to 14. The inner tube *b* is initially circular in section, but in the last portion of the die it becomes flattened slightly in the neighborhood of the joint in the case. No special provision is therefore required in the preparation of the inner tube to accommodate 20 the additional thickness of the case at the joint caused by the inturned edges of the case and the locking strip. The configuration of the outer periphery of the finished tube is circular throughout. In the drawings the thickness of the case is exaggerated for clearness of illustration. In 25 practice the extra thickness of metal at the joint and the flattening of the inner tube at that part is scarcely appreciable to the eye.

The invention is not limited to cylindrical tubes but may be applied to tubes of rectangular or any other desired cross section. 30

By the means and procedure hereinbefore described tubes of superior finish or appearance can be readily produced, and as thinner cases can be employed than is ordinarily permissible the tubes can be manufactured at 35 correspondingly smaller cost.

We claim;

1. In means for producing metal cased tubes, the combination comprising a die having 40 an aperture adapted to close a case strip around an inner tube, simultaneously with the drawing of the said strip and tube together through the die, and a guide piece whereby a locking strip is directed into position

between the inner tube and case strip, 50 for engaging the edges of the latter, substantially as described.

2. In means for producing metal cased tubes, the combination comprising a die provided with an aperture the shape of which 55 changes continuously from an oval section at one end to a circular section at the other end, a central ridge extending along a portion of the die, and a guide piece slotted at its underside, substantially as described. 60

3. In means for producing metal cased tubes, the combination comprising a die provided with an aperture the shape of which continuously changes from an oval section 65 at one end to a circular section at the other end, a central ridge extending along and made integrally with a portion of the die, and a loose guide piece slotted at its underside and adapted at its upper side to abut against the die for preventing longitudinal 70 movement of the guide piece with the work, substantially as described.

4. In means for producing metal cased tubes, the combination comprising a die composed of sections with apertures in alignment, one of the sections being formed with a trough shaped aperture, a cover plate attached to the section with trough shaped aperture and adapted to form therewith an aperture of oval section with a central ridge, 75 a central ridge formed with and extending along a portion of the aperture in the other die sections, a loose guide piece slotted at its forward end and along its underside and shaped at its upper and lower surfaces to a 80 convex and concave configuration respectively, and a projection formed with the guide piece for abutment against a slotted portion of the cover plate, substantially as 85 described. 90

In testimony whereof we have signed our names to this specification in the presence of two subscribing witnesses.

JOHN WILLIAM EARLE.
ALFRED BOURNE.
